MULTIPLE TEMPERATURE REFRIGERATOR
Michael H. Devery, Ambler, Pa., assignor to Philco Corporation, Philadelphia, Pa., a corporation of Pennsylvania

Filed Aug. 25, 1959, Ser. No. 835,934
4 Claims. (Cl. 62—186)

This invention relates generally to the field of refrigeration and more particularly to an improved method of and means for refrigerating plural compartment refrigerators.

It is now recognized that it is desirable to provide within a refrigerated cabinet not only a food storage compartment maintained at temperatures above the freezing point of water, in order to provide for the proper preservation of food stuffs which should not be subjected to subfreezing temperatures, but also a compartment maintained at sub-freezing temperatures suitable for the preservation of frozen foods over long periods of time.

A technique presently employed for comparting the refrigerator is to use an insulating baffle to partition the cabinet into upper and lower food storage zones. A widely used refrigerating arrangement provides for a predetermined leakage of refrigerated air from the cooler chamber to the warmer. This arrangement while satisfactory from many standpoints results in a reduction in the temperature control over each of the food storage compartments, a condition which has heretofore been remediable only by the use of separate cooling elements in heat exchange relation with each of the refrigerated zones, a solution which is costly and space consuming.

It should also be understood with respect to constructions of the last mentioned type that without resort to independent cooling means the recovery time of the dependent warmer compartment is not as rapid as it should be under many conditions of operation. The temperature of this compartment can become unduly elevated by the inflow of warm air from the room in which the refrigerator is located, the interchange of air between compartments under such conditions not being sufficiently rapid to maintain the required protective food storage temperatures.

On the other hand accepted methods of providing forced draft interchange of refrigerated air between compartments utilizing a single cooling element, in an effort to improve recovery time of the dependent chamber, results in dehydration of the food within the food storage compartment through condensation of the air's moisture upon exposed cooler surfaces of the cooling element.

Accordingly, it is an object of this invention to provide a novel single-evaporator refrigerating system which achieves complete structural isolation between refrigerator and freezer compartments, while providing selective cooling of each compartment in response to the individual temperature conditions prevailing therein.

It is another object of this invention to provide a single-evaporator cooling system which insures separate and controlled cooling of each compartment, in addition to eliminating the problem of food dehydration.

It is a still further object of this invention to provide a single-evaporator refrigerating system which can be readily associated with and removed from the refrigerator as a unitary structure and which provides substantially completely selective refrigeration of a plural compartment refrigerator.

Another but subordinate object of this invention is to provide a unitized inexpensive refrigerating system of extreme structural compactness and simplicity.

These and other objects within contemplation will be

2

apparent by reference to the accompanying detailed description and drawings in which:

FIGURE 1 is a longitudinal sectional view taken generally through the medial plane of a refrigerator embodying one form of the invention, certain control circuitry being illustrated diagrammatically;

FIGURE 2 is an exploded view of a unitized, single-evaporator cooling system made in accordance with the present invention;

FIGURE 3 is a perspective showing diagrammatically illustrating one mode of installing the unitized cooling system within a plural compartment refrigerator;

FIGURE 4 is a sectional view taken along the cutting plane 4—4 of FIGURE 3 depicting certain features of construction of the refrigerator inner liner; and

FIGURE 5 is a detailed sectional view (with the elements of the refrigerating system shown in elevation and in installed position) of the freezer portion of the refrigerator shown in FIGURE 1.

Now making more particular reference to the drawings and especially to FIGURE 1, it will be seen that the invention is illustrated as embodied in a domestic refrigerator here chosen for illustrative purposes as an 18 cubic foot box having a 6 cu. ft. freezer and a 12 cu. ft. food storage compartment. The box comprises an outer shell 10 and an inner shell or liner member 11 shaped as shown in FIGURE 4 and spaced inwardly of and insulated from the outer shell 10 by any suitable insulation shown at 12. As is customary, a breaker strip 13 of low thermal conductivity extends about the forward edge of the cabinet and bridges the gap between the outer shell 10 and inner liner 11. The refrigerator also includes a machine compartment 14 housing an assembly consisting of the motor-compressor unit 15, fan 16 and fin-tube condenser 17, the construction being adapted for forced draft operation of the high side of the system. The compressor and condenser may be of any desired type, and as will be understood, are connected in refrigerant flow circuit with the evaporator 18, the connecting tubing and auxiliary components being omitted from FIGURE 1 for clarity of illustration, the circuitry being shown in detail in FIGURES 2 and 5.

The space defined by the shell 10 is subdivided into a lower freezer compartment 19 and an upper, above-freezing compartment 20 by means of the partitioning wall 21. Each of the compartments is provided with its own door 22 and 23, respectively, adapted to seat in air tight closure against the cabinet in the plane of the breaker strip 13.

In the embodiment shown the evaporator 18 is positioned in high heat exchange relation with the freezer compartment 19 in the novel manner hereinafter described. It should be understood however that while the invention is illustrated in connection with a so-called "upside-down" refrigerator it is not to be considered as being limited to such use, the invention being applicable to refrigerators of alternate design. In the construction shown the compartments 19 and 20 share a common cooling plenum 25, within which is located the evaporator 18.

The plenum 25, in particular accordance with one aspect of the invention, is formed as part of a single-evaporator unitary refrigerating system, shown in exploded view in FIGURE 2, which can be readily associated with and removed from a multi-chamber refrigerator in the manner clearly indicated in FIGURE 3. This system, in conjunction with air moving means such as a pair of fans, provides cooling of each compartment selectively and in response to the individual temperature conditions prevailing in each thereof.

The cooling plenum is defined by baffles 26 and 27, the construction being most clearly shown in FIGURE

5. Baffle 27, in cooperation with ducts 28 formed by the juncture of the metal food storage compartment shell 29 and the preformed ribs of liner 11, provide a substantially closed flow circuit for refrigerated air around the shell 29 and back to the cooling plenum 25. One pattern of ribbing 30 designed to insure uniform distribution of refrigerated air over the surface of the food compartment shell 29 is shown in FIGURE 4. A second independent flow route for the circulation of refrigerated air between the freezer 19 and plenum 25 is provided by ports 31 and 32 formed in baffle 26. This baffle, forms the dividing wall between the freezer compartment 19 and cooling plenum chamber 25. Controlled movement of air through the two systems is accomplished by the use of strategically positioned fans 33 and 34.

In the illustrated embodiment the desired selectivity of flow is attained by placing a fan in communication with each of the mentioned passageways in the locations shown in FIGURES 1 and 5. Fan 33 which controls the refrigeration of the freezer compartment 19 is disposed centrally at the upper rear of the freezer compartment, its blading being positioned within port 31 in the plane of baffle 26. A fan having a capacity of 30 c.f.m. is adequate for refrigerating the freezer compartment. Operation of this fan produces circulation of air between the freezer and the cooling plenum 25, the direction of flow being indicated by the arrows shown in FIGURE 5. The blading of fan 34, on the other hand, the motor housing of which is seated within the foamed plastic core 35 of the detachable wall plug (see FIGURE 2) is positioned within port 37 of the rearmost baffle 27, and is mounted and rotated in such direction that, when energized, air is circulated upwardly through ducts 28 surrounding the food compartment 20 and back to the cooling plenum 25. The required capacity of this fan is about twice that of the freezer fan and it may be of the impeller type (not shown) when the cabinetry conveniently admits of such construction. The flow pattern induced by fan 34 is schematically indicated by arrows in FIGURE 1.

To improve the heat exchange relation between the structurally isolated food storage compartment 20 and the refrigerated air surrounding it, the shell 29 is preferably made of aluminum or other material having low thermal impedance.

As will be understood from what follows, by employing the method of the present invention the problem of food dehydration in both freezer and refrigerator is eliminated as is the need for a separate cooling element with its expensive and hard to assemble complex of tubing. In addition the unique arrangement shown provides separate and differential cooling of each compartment substantially independently of the refrigeration needs of the other in a manner insuring minimal recovery time in each compartment.

A satisfactory control circuit for accomplishing selective refrigeration is described below, it being understood that, insofar as the concepts of this invention are concerned, the circuitry is merely illustrative of one convenient mode of achieving the desired result.

Referring to FIGURE 1, it will be noted that the refrigerator is provided with a trio of temperature-responsive control elements 40, 41 and 42, each of said elements, through the agency of conventional control bulbs, being adapted to initiate operation of instrumentalities within the system. Element 40 for example is provided with a control or feeler bulb 43 disposed in heat exchange relation with the surface of evaporator 18 the bulb being partially sheathed in material of low heat conductivity to insulate it from the air stream passing over the evaporator, for reasons hereinafter set forth. When the temperature of the evaporator has risen sufficiently to expand the bellows of element 40 the contacts of switch 44 are closed placing the motor-compressor unit 15 across the line.

Similarly bellow elements 41 and 42 are respectively provided with feeler bulbs 46 and 47. When the temperature of the food compartment 20 has risen to a predetermined value, bellows 42 closes the contacts of associated switch 48 energizing fan 34, resulting in circulation of cooling air through ducts 28.

Control element 41 is likewise actuated when the temperature within the freezer compartment rises above a predetermined value. When this occurs contacts 51 are closed energizing fan 33 which in turn initiates circulation of air between the freezer and cooling chamber. As an additional refinement the circuit to each fan is completed through a door operated switch 52 of conventional type which is maintained in closed position when door 22 is closed, and which opens the circuit to the fans when the freezer door is opened in order to prevent loss of refrigeration through the expulsion of cool air, or the drawing in of warm air by the operating fans.

The arrangement described provides the desired selectivity of control by insuring substantial isolation of the air in the different cooling systems while realizing the advantages of single-evaporator economy, localization of frost in a zone outside the refrigerated compartment without food dehydration and minimal recovery time of the separate cooling chambers through utilization of the full cooling capacity of the evaporator to meet the individual refrigeration demands of each chamber.

To facilitate a clearer understanding of the invention a representative set of operating parameters and conditions will be described, the refrigerator chosen for illustration being the above mentioned 18 cubic ft. box having a 6 cu. ft. freezer and a 12 cu. ft. foot storage compartment. Preferably the foot storage temperature sensing element 47 is designed to operate over a temperature range of from 34 to 40° F., the bulb being positioned within the upper, warmer part of the food compartment.

In accordance with the invention the temperature of the food storage compartment inner walls, formed by tub 29, are maintained at a temperature above the freezing point of water. By isolating the air within the refrigerator compartment from the cooling coil 18 and maintaining the compartment's inner walls at a temperature above freezing, the problem of frost accumulation, and consequent excessive dehydration, is completely avoided.

Moreover, this arrangement insures that the humidity will not become excessively high by promoting condensation of warm humid air entering the enclosure on its contact with inner wall surfaces maintained at temperatures below the air's dew point. Where moisture accumulation brought about by this process may become excessive, as might be the case in certain geographic areas, the surplus water can readily be removed by means well recognized in the art, as for example by use of a sump 29' and appropriate drain means not shown.

The freezer temperature is controlled by the bulb 46 which has an operating range of 0 to -10° F., while the surface temperature of evaporator 18, positioned within 60 the cooling plenum 25 is monitored by a temperature sensing bulb 43 operating between 0 and -15° F., the latter bulb controlling the operation of the motor-compressor unit 15.

When the system is initially energized the motor-compressor unit 15 and fans 33 and 34 are simultaneously activated each fan circulating refrigerated air to its respective compartment substantially independently of the other. When the predetermined temperature conditions of each compartment are met, the fan associated with 70 that compartment is automatically shut off, for example, if the refrigerating conditions of the food storage compartment have been satisfied the bellows 42 associated with that compartment constricts, opening the electrical connection to fan 34.

75 The freezer in the meantime may still require addi-

tional refrigeration in which case fan 33 remains energized circulating air between the freezer and evaporator 18 until the desired temperature conditions of that particular compartment are established. When this occurs the electrical connection to fan 33 is interrupted in a manner similar to that described for fan 34. The compressor may continue to run for a brief interval of time after freezer temperatures have been reached, until the evaporator reaches some predetermined lower temperature as for example -15° F.

To avoid overloading the compressor, where heavy usage results in a condition in which refrigeration in one or the other of the compartments is required immediately after shutdown of the compressor, the sensing element 43 mounted to the evaporator is insulated from the ambient air by a protective sheath to provide a thermal time delay of from five to eight minutes this technique being well known in the art. By this means the relatively warm air which is drawn into the cooling plenum from, for example, the food compartment cooling ducts, does not result in immediate energization of the compressor and permits pressure equalization within the refrigeration lines before the next cycle of operation is initiated. Moreover, this expedient enables full use to be made of the residual cooling capacity of the evaporator which is designed to have sufficient thermal mass to provide the required refrigeration during unusual operating conditions of the nature described.

Constructional details of this unique refrigerating system are shown in FIGURES 2 and 5, the system being designed so that it can be completely assembled, sealed, and tested prior to its insertion within the structure being refrigerated. One constructional arrangement is to consolidate the elements comprising the cooling chamber into a readily insertable plug 60. This plug, shown in exploded view in FIGURE 2, may conveniently consist of a steel plate or shell 61 having mounted thereto an expanded plastic foam facing or core 62 provided with suitably molded cavities 63. The core may be made of any of numerous types of expandable foamed plastics, for example, to mention a few, phenolic, styrene, vinyl and isocyanate, in addition to the reactant type plastic mixtures, as exemplified by allyd-resin-methyl-toluene-diisocyanate. The cavities formed in this core receive the various circuit components such as the defrost valve 64, accumulator 65, tubing 66 and refrigerator fan 34. The components when positioned within these respective cavities are securely held in place by a mating foamed plastic slab 67, containing a pattern of cavities similar to that found on core 62, the components being sandwiched therebetween. The face of slab 67 which confronts baffle 27 is centrally relieved to provide side rails 71 against which baffle 27 seats to form the air passageway 72. Positioned forward of baffle 27 is the evaporator 18 followed by baffle 26, the entire assembly being suspended on bolts 73 secured to fasteners 74 (see FIGURE 5) carried by Masonite strips 75 mounted to the steel plate 61.

To improve the support strength of the bolts they are provided with a nut and washer assembly 76, located on an opposite face of the support in opposed, spaced relation to each fastener, the assembly being drawn down snugly against the support 75 to form a compressive lock. Spacers 77 may be used to position baffle 26 relative to the evaporator 18, and freezer fan 33 may conveniently be mounted to the evaporator top. The motor housing of fan 34 is removably seated within a suitable cavity provided in core 35. The fan is secured by screws 80 fitted into internally threaded bushings 81 entrapped within the body of the core. The assembled unit ready for installation is shown in FIGURE 3.

Appended to the assembly 60 is the high side of the system comprising the motor-compressor 15, condenser 17 and fan 16, these units being mounted on a common frame 82 which in turn is mounted to the assembly 60 by metal support braces 83.

The unit as thus assembled may be easily inserted within the cavity 84 provided in the rear wall of the refrigerator cabinet. When inserted the unit is locked in place by simply screwing the apertured flange of steel shell 61 to the rear wall of the refrigerator and fastening frame 82 within the machine chamber 14. To improve the seal between the rear wall of the refrigerator and the flange 86 the mating surface of the wall may be coated with any one of a number of well recognized sealants, such as for example permagum. The braces 83 may be retained as a permanent part of the installation or be removed for use in subsequent installations.

To facilitate alignment of baffle 27 with the lower rear edge portion 89 of shell 29, the baffle is contoured at 90 15 to receive the tub edge. To compensate for tolerance variations while at the same time insuring substantially air tight seating of the baffles, the baffles are provided with squeeze-like gasket element 91, which during installation act to seal off the cooling plenum from the remainder of the system.

In summary there is provided a unique single-evaporator refrigerating system which can be readily associated with and removed from a refrigerator. This system through a novel arrangement of fans provides substantially completely selective refrigeration of a plural compartment refrigerator having the advantages detailed above.

Although the invention has been described with particular reference to specific practice and embodiments, it 30 will be understood by those skilled in the art that the apparatus of the invention may be changed and modified without departing from the essential scope of the invention as defined in the appended claims.

I claim:

- 35 1. In a plural compartment refrigerator, the combination comprising: duct means in heat exchange relation with exterior surfaces of one of said compartments; a plenum containing an evaporator mounted to a removable rear wall portion, said evaporator being disposed in high heat exchange relation with the other of said compartments and separated therefrom by a partition apertured to provide a passage for the circulation of air between said plenum and said other of said compartments; means forming a communicating passageway between said plenum and duct means; and air circulating means disposed in each of said passages selectively to control the movement of refrigerated air therethrough in response to the individual temperature conditions of said compartments.
- 40 2. In a refrigerator having a freezer and food storage compartment, the combination comprising: air conduit means for piping refrigerated air around said food storage compartment; a cooling plenum disposed in high heat exchange relation with said freezer compartment and containing an evaporator carried by and bounded on one side by a separately formed, removable rear wall portion of said refrigerator and on an opposite side by a baffle forming the rear wall of said freezer compartment, and said baffle being apertured to permit circulation of air between said plenum and freezer, means providing a communicating passage between said plenum and conduit means; and a pair of fans operative to force air through said plenum to provide substantially completely selective refrigeration of said compartments in response to temperature conditions prevailing in each thereof.
- 45 3. In a refrigerator having a freezer and food storage compartment, the combination comprising: duct means in heat exchange relation with exterior surfaces of said food storage compartment; a single-evaporator refrigerating assembly positioned within a suitable opening provided in the rear wall of said freezer compartment, said assembly comprising, an insulative plug sealing said opening, an evaporator and baffle, said plug and baffle co-operating with interior wall portions of said freezer com-
- 50 70 75

partment to form a separate cooling plenum within which said evaporator is housed, said baffle being apertured to provide a path for the circulation of air between said freezing compartment and plenum and said assembly being further provided with conduits communicating with said duct means to form a closed path of flow for the circulation of refrigerated air from said plenum through said duct means; and a fan disposed in each of said paths providing substantially completely selective refrigeration of said compartments in response to temperature conditions prevailing in each thereof.

4. In a plural compartment refrigerator, the combination comprising: duct means in heat exchange relation with one of said compartments; a cooling plenum containing an evaporator, said plenum being disposed contiguous the other of said compartments and separated

therefrom by a partition apertured to provide a passage for the circulation of air between said plenum and said other of said compartments, means forming a communicating passageway between said plenum and duct means; and air circulating means for selectively controlling the movement of refrigerated air through each of said passageways in response to individual temperature conditions existing in each of said compartments.
